WILFRED R. V. MARSHALL, OF PAISLEY, SCOTLAND.

DYNAMO-ELECTRIC MACHINE OR MOTOR.

SPECIFICATION forming part of Letters Patent No. 694,293, dated February 25, 1902.

Application filed November 8, 1901. Serial No. 81,574. (No model.)

To all whom it may concern:

Be it known that I, WILFRED ROBERT VERNET MARSHALL, a subject of the King of Great Britain and Ireland, and a resident of Paisley, in the county of Renfrew, Scotland, have invented certain Improvements in Dynamo-Electric Machines or Motors, of which the following is a specification.

My said invention has for its object to improve the construction of pole-faces of the field-magnets of dynamo-electric machines and motors, so that the reaction of the armature shall be checked to a large extent, thus enabling a number of practical advantages to be obtained—such, for example, among others, as comparatively nearly sparkless commutation—and increasing the capability of the dynamo or motor to take overloads with very small risk of damage.

My improved pole-face may be constructed in various ways; but in all the modifications it consists, essentially, of laminated plates of iron or steel with intervening non-magnetic spaces between each plate or set of two or more plates, transverse non-magnetic spaces being also formed in some cases, if desired. The plates may be secured in any suitable manner; but they are by preference arranged in groups and strung on binding-rods, so that each series of groups overlap or break joint and so that the greatest breadth is at the center of the pole-face.

Figure 1 of the accompanying drawings is an elevation, partly in section, of one modification of my improved pole-face, showing a part of the pole to which it is attached. Fig. 2 is an inverted horizontal section of the said pole-face. Fig. 3 is a diagrammatic face view of the pole-face with the iron irregularly distributed.

In carrying out my invention according to the modification shown in Figs. 1 and 2 each pole-face consists of a number of standard segmental iron or steel plates A, curved to suit the armature (not shown) and having holes formed through them, so that they may be strung on binding-rods B, extending between side plates or cheeks C. The plates A are by preference arranged in sets of two or more plates each, (three being shown in this example,) distance-pieces D being placed between adjacent sets of plates and between them and the side binding-plates C, where

necessary, so that the plates A are held in such a way that spaces E are left between adjacent sets of plates. Instead of the plates A being in sets single plates may be used, as indicated in Fig. 3.

The relative amounts of metal and non-magnetic spaces in the pole-face are dependent upon the class of work the dynamo or motor has to do, whether there is to be a constant load or not, power of taking overload, whether or not to run equally well in either direction of rotation, also upon the material used in the pole-face and field, also quality of iron in armature; but a description of the action of the pole-face will explain the best construction to select.

In Fig. 1, assuming the armature of a dynamo as revolving clockwise, the reaction or distorting effect of the armature will tend to reduce the density at K and increase it at G. Now the length of the iron of the pole-face at G and the density (magnetic density, therefore indirectly the sectional area of the iron at G) must be so selected that when the armature reaction comes into effect attempting to strengthen the field the magnetic reluctance shall be such that it prevents too high a density (magnetic) occurring, and if the iron is worked at a fairly high density it is well known that a considerable increase in the magnetizing power only increases the amount of magnetism very slightly. Therefore with my construction of pole-face a rising power of magnetism, such as occurs at point G in this case, does not give a proportional rise in magnetism, such as would occur were the ordinary air reluctance depended upon. In a like manner at point K, where the field is being reduced, the reduction of magnetism is not so great, as the iron acts as a sort of spring, and as the density falls away, or, more correctly, as the magnetizing power gets opposed by the armature's reaction, the magnetism does not fall away in proportion as it would do with an ordinary air reluctance; but the iron of my pole-face now (that is to say, at a reduced density) only requires very little power to drive the lines across it, and thereby you keep what may be called a "reserve power" that comes into action on the air-gap and keeps up the density. It will also be observed from the foregoing that it is not essential to have a regular section of air and

iron throughout the pole-face; but beneficial results could be obtained by selecting the sections throughout the length to suit any special construction of a machine for special duties, 5 such as a dynamo or motor running in one direction and having a constant load. You could then arrange your plates so that at this special load you would attempt to keep the magnetic field as near a constant density as 10 possible, as you would then get maximum output with minimum "hysteresis" losses, as the hysteresis losses are dependent upon the highest density, and instead of having only the trailing pole-tip, or, more correctly, the air-gap 15 under the trailing tip, at a high density you could arrange to keep the density high throughout the whole length, thus increasing the output of the machine.

It will be seen that the relation of section 20 and length of iron in pole-face at certain points instead of being of regular construction, as shown, may be regular, dependent upon specific results required and also dependent upon class of materials used. Thus 25 in the diagram, Fig. 3, I have indicated the plates as grouped or assembled in greater or closer mass in certain parts of the pole-face than in others, and at x I have indicated the plates of one group overlapping the plates of 30 another group, still leaving the air-gaps, hereinafter referred to, substantially at right angles to the path of the armature's magnetic 35 reaction. This method of governing the field's distortion gives comparatively sparkless commutation under all conditions of working and enables a reduction in the number of commutator-sections to be effected. Hysteresis losses in the armature are also reduced, enabling the size of the armature to be reduced. 40 A saving in copper is also effected through reduction in the number of "ampere turns" on the field-magnets necessary to obtain the necessary field for sparkless commutation with consequent reduction in the size of the 45 field-magnets and yoke. To assist in obtaining these results, additional air or non-magnetic gaps or spaces L may also, if desired, be introduced into the path of the magnetic lines of force produced from the armature by arranging the plates A and non-magnetic spaces E in a series of groups M and leaving the spaces L between the ends of the 50 groups M . The groups M may be attached to the pole P by screws (shown by dotted 55 circles Q in Fig. 2) and are so strung on the binding-rods B or otherwise secured together that the several series of groups M overlap or break joint, the greatest breadth being at the center of the pole-face, Fig. 2, and this enables the armature-conductors to gradually 60 come into the magnetic field and to leave it in the same way, (as happens when a round pole-face is used,) thus doing away with the necessity of opening out the main air-gap J 65 at the point where the armature-conductors enter and leave the magnetic field in order to prevent damage to the teeth of the armature.

and vibration and also giving an "iron reluctance" for the armature's reaction or distorting effect to work upon, which under my 70 method of construction assists in obtaining the desired result of checking the distorting effect of the armature's reaction. Instead of building up the pole-face so that its greatest breadth is at the center my improved construction of laminated plates A and intervening non-magnetic spaces E may be grouped or held together so that the face will be of the usual rectangular form, and where the transverse non-magnetic spaces L are not used the 75 plates may be in one continuous length, if desired.

I claim as my invention—

1. A pole-face for a dynamo-electric machine or motor, comprising laminated groups 85 of metal plates, spaces between the ends of such groups, the outside groups forming a face of less breadth than the center ones and the intermediate groups being in step-like position between the center and outside groups, 90 substantially as described.

2. A pole-face for dynamo-electric machine or motor, comprising laminated groups of metal plates, spaces between the plates of the groups, spaces between the ends of the groups, 95 and said groups being arranged step-like from the outside toward the center, substantially as set forth.

3. A pole-face for a dynamo-electric machine or motor, having standard plates 100 mounted in groups, the plates of each group being spaced apart from each other, substantially as described.

4. A pole-face for a dynamo-electric machine or motor, having standard plates 105 mounted in groups, the plates of each group being spaced apart and being made short to leave transverse air-gaps in said pole-face, substantially as described.

5. A pole-face for a dynamo-electric machine or motor, comprising plates mounted 110 in groups, the plates of each group being spaced apart, transverse slots in said pole-face, said metal plates forming a face of greatest breadth at the center of the pole-face, and diminishing in breadth in step-like 115 manner toward the side, all substantially as described.

6. A pole-piece for a dynamo-electric machine or motor having a greater proportion of 120 metal in one part than in another, and consisting of a number of standard metal plates assembled in such a manner as to produce a pole-face having different masses of iron in such places as it may be required according 125 to the use of the machine, substantially as described.

In testimony whereof I have signed my name to this specification in the presence of two subscribing witnesses.
